GASOLINE STOVE

George E. Pickup, Newark, Ohio, assignor to The Wehrle Company, Newark, Ohio, a corporation of Ohio

Application March 24, 1933, Serial No. 662,406

7 Claims. (Cl. 158—42.4)

The invention pertains to gasoline cook stoves, and has more particular reference to a thermostatically actuated valve means for cutting off the supply of liquid fuel to the generator in case of the accidental extinguishment of the burner.

The primary object of the invention is to provide a thermostatically actuated valve means of the character indicated which is simple in construction and certain in its operation, and otherwise of a very practical character.

A further object is to provide a valve for controlling the fuel supply, which is arranged for actuation by a thermally responsive element associated with one of the burners and located in a relatively cool zone in the burner box, thereby avoiding difficulties on account of the accumulation of carbon in the valve.

The objects of the invention thus generally stated together with other and ancillary advantages, are obtained by the construction and arrangement illustrated in the accompanying drawing, in which:

Figure 1 is a fragmentary top plan view of a burner structure for gasoline cook stoves and embodying my invention.

Fig. 2 is a vertical sectional view on an enlarged scale taken approximately in the plane of line 2—2 of Fig. 1.

In the preferred embodiment of the invention, the burner structure comprises a main burner having two laterally spaced segmental sections 3 mounted upon and communicating with an arm 4 of a manifold 5. Fuel is supplied in gaseous form to the manifold through the medium of a goose-neck 6, from a tubular generator 7 interposed between the two burner sections 3. Control of fuel to the burner 3 is effected by means of a suitable valve (not shown) having an operating rod 8, and in constant communication with the manifold is a generator burner 9 in the form of an elongated tubular member disposed beneath the generator 7 and connected at its rear end with an angular arm 10 of the manifold. 11 designates a fuel supply pipe leading from the upper portion of the usual supply tank (not shown) and connected with the manifold for supplying fuel vapor thereto for starting purposes in a well known manner. At the point of discharge of fuel vapor into the manifold from the pipe 11, a secondary air mixing device 12 is provided.

The generator 7 comprises in the present instance primary and secondary tubes 13 and 14 arranged in parallel relation between the two main burner sections 3 and communicating with each other at their forward ends through a fit-

ting 15. Fuel in liquid form is supplied to the rear end of the primary tube 13 by means of a pipe 16, and fuel in gaseous form is delivered by the secondary tube 14 into the gooseneck 6 of the manifold. The tube 14 is for this purpose equipped with the usual needle valve (not shown) which is disposed in the discharge end of the tube and operated by a rod 17 extending through the tube and through the fitting 15 at the forward end thereof. The construction of the generator 10 thus generally set forth forms no part of the present invention, but is fully disclosed and claimed in my copending application Serial No. 662,407, filed March 24, 1933.

As shown clearly in Fig. 1, the supply pipe 16 extends laterally away from the rear end of the primary tube 13 and thence forwardly for connection with a control valve 18, which in accordance with my invention, is arranged for thermostatic actuation by a thermal element in the form of a rod 19 disposed transversely of the generator and having one end interposed between the forward ends of the generator tubes and the forward one of a plurality of grids 20 in the generator burner 9. Thus, the valve 18 is located 20 remotely from the generator and associated burners within a relatively cool zone in the burner box of which I have shown at A only a portion of the front and side walls. Thus the valve is not subjected to the intense heat issuing from 30 the burners. In this latter connection, I have discovered that when the control valve is arranged in close association with the generator and the burners, difficulties arise on account of accumulation of carbon in the valve.

Referring now to Fig. 2, the valve 18 comprises a body or casing 21 having a valve member 22 therein controlling the flow of fuel to the pipe 16 which is connected to one side of the valve casing in communication with a longitudinal passage 23 extending through the casing. Fuel in liquid form is supplied to one end of the casing by means of a pipe 24 leading from the fuel supply tank (not shown) and connected to the valve casing by means of a coupling 25 which 45 may be equipped with a strainer 26. The valve 22 has a stem 27 of a diameter smaller than the diameter of the passage 23 at the point of communication with the pipe 16, the casing having an outlet port 28 with which the pipe 16 is connected.

The thermally responsive valve actuating rod 19 extends through the end of the valve casing 21 opposite the supply pipe 24, the casing being provided for this purpose with a suitable packing 55.

gland 29. Within the casing the rod 19 is made rigid with the valve stem 21. The opposite end portion of the rod 19 overlies the forward grid 20 of the generator burner and is fastened in an upstanding arm 30 of a stationary bracket 31. This arm 30 is spaced a short distance from the side of the burner grid 20 opposite the valve 18, and rod 19 has its end portion threaded for engagement with an internally threaded aperture 10 in the arm for adjusting purposes. A nut 32 rigid with the rod facilitates the adjustment of the latter in the bracket arm 30, and a lock nut 33 is preferably provided on the free end of the rod. The bracket 31 extends transversely with 15 respect to the generator tubes and provides a support for the forward end of the generator burner 9 as well as for the rod. At the end opposite the arm 30 the bracket has an apertured arm 34 encircling the valve casing and fastened thereto as by means of a nut 35. Thus the bracket serves to maintain the valve and the anchored end of the rod 19 in a fixed relation.

It will be understood that the rod 19 is made of a material which is adapted to expand and contract in an endwise direction according to whether or not the generator burner 9 is in operation; and the parts are so proportioned that the valve member 22 is firmly held tightly against its seat in the valve casing when the rod is cold, 20 and is moved away from its seat when the rod is heated. Moreover, it will be seen that inasmuch as the rod is subjected directly to heat from the generator burner in the initial or starting operation during which fuel is supplied by the pipe 14, the rod 19 becomes heated as an incident to the 25 heating of the generator tubes. Thus, as the latter are being conditioned for the reception of liquid fuel from the pipe 16, the rod 19 is expanded to open the valve 18 and permit the supply of fuel to the generator tube 13. Conversely, if for any reason, the generator burner should 30 become extinguished during the operation of the stove, the rod 19 will cool off rapidly and close the valve 18, thus interrupting the supply of fuel 35 to the generator to avoid the danger from explosion.

It will be observed that while the construction employed is simple and inexpensive from a manufacturing standpoint, it is advantageous because 40 it permits of the location of the control valve within a relatively cool zone and thus avoids difficulty on account of the accumulation of carbon in the valve. Moreover, I have found that in practice, the supply of fuel to the generator is 45 reliably controlled in a manner such as to insure safety of operation.

I claim as my invention:

1. A burner structure for gasoline stoves, comprising in combination, a tubular generator, a burner arranged to supply heat to said generator, means for supplying fuel to said generator including a control valve having a movable valve member, an elongated supporting bracket extending transversely of said generator and supporting said valve at a point remote from the burner, and thermally responsive means for operating said valve member including a rod having one end rigid with the valve member and its other end fixed on said bracket on the end opposite the valve.

2. A burner structure for gasoline stoves, comprising a burner manifold, an elongated tubular generator having one end discharging into said manifold, a generator burner in the form of an elongated tubular member connected with said

manifold and underlying said generator and having a burner grid at the end opposite the manifold, an elongated bracket secured to the forward end of said generator burner transversely thereof, means for supplying fuel to said generator including a control valve secured on one end of said bracket a substantial distance to one side of said burner, and temperature responsive means for operating said valve including an elongated thermal element disposed between said burner grid and said generator and secured on the end of the bracket opposite the valve.

3. In combination with a burner structure comprising, a tubular generating member communicating with the burner and positioned for being heated thereby, a valve controlled fuel supply for said generator including a valve disposed a substantial distance from said burner and generating member, a rod with one end operatively connected with said valve and its other end interposed between said generator and said burner, and a common means integral with the burner structure supporting said last mentioned end of the rod and said valve in given relation, said rod being adapted to expand when subjected to heat from the burner to open said valve.

4. In a device of the character described, the combination with a burner, of a generator comprising a tubular member communicating with the burner and positioned for being heated thereby, a valve controlled fuel supply for said generator including a valve disposed laterally to one side of the generator, a stationary bracket on the opposite side of the generator, a rod with one end operatively connected with said valve and its other end extending between said generator and said burner and having a screw threaded engagement with said bracket, said rod being adapted to expand when subjected to heat from the burner to open said valve, and means on the rod for turning it to adjust said valve member.

5. In a structure of the character described, the combination with a burner of a generator including an elongated tube communicating with and positioned adjacent the burner so as to be heated thereby, a liquid fuel conducting system leading to said tube and including a casing and a valve therein disposed laterally a substantial distance to one side of the tube and the burner, a thermally expansible rod extending transversely of said tube with one end operatively connected with said valve and with only a small portion of its other end extending between the generator and burner, and stationary supporting means including a part fixedly supporting said casing and another part on the opposite side of said generator and fixedly supporting the said other end of said rod, whereby expansion of said rod will move said one end and open said valve.

6. In combination with burner means in a vaporizing liquid fuel stove, an elongated generating tube positioned to be heated by said burner means, a manifold at one end of said tube and in communication therewith for conducting vaporized fuel mixture to said burner means, a fuel delivery system including a conduit for delivering liquid fuel to the opposite end of said generating tube wherein the fuel is heated and vaporized before passage to said manifold, a valve in said delivery system in communication with said conduit separate from and remotely positioned relative to said generating tube and said burner means so that the valve will remain cool and substantially unaffected by heat from

5 said burner means or from said tube, a thermally responsive rod extending transversely of said generating tube with a small portion adjacent the inlet end of the tube opposite said manifold arranged to be heated by said burner means, one end of said rod on one side of said tube being operatively connected with said valve, and means including a part for supporting the latter end of said rod for longitudinal movement 10 and a part on the opposite side of said tube providing a rigid connection for the remaining end of the rod, whereby said one end of said rod will be moved longitudinally upon expansion or contraction of said rod and respectively open 15 or close said valve.

15 7. In combination with a burner structure for gasoline stoves comprising an elongated tubular generator communicating with a burner spaced from said generator and in position to heat the same, a fuel supply conduit, valve means including a body having an elongated passage extending therethrough with the end of said con-

duit connected to the inlet end of said passage and an outlet port communicating with said passage from one side of the body, a rod of thermally responsive material having one end extending slidably into said passage through the extremity thereof opposite said conduit and its opposite end extending with only a small portion in proximity to said generator in such relation as to be heated by the burner, stationary means including a part supporting said body 10 at a substantial distance from said burner and generator and another part fixedly supporting said opposite end of said rod, and a valve member operable by the end of said rod within said passage and disposed between said outlet port 15 and the inlet end of said passage to maintain said passage normally sealed against liquid flow when said rod is in contracted condition and opening said passage to permit liquid flow when said burner is lighted and said rod expanded. 20
